FASTENING DEVICE FOR TRUSS AND OTHER
BANDSGilbert Thomas Walker, Birmingham, England,
assignor to Thomas Walker Limited, Birmingham,
England, a company of Great BritainApplication November 1, 1937, Serial No. 172,078
In Great Britain July 30, 1937

5 Claims. (Cl. 24—79)

This invention relates to bands, straps and the like, where the one band is disposed at an angle to the other, the invention having more particular reference to trusses or surgical devices comprising a main body band and an auxiliary or under band attached thereto, such auxiliary or under band usually depending from the main band, so as to pass between the legs of the wearer, and being generally attached to a loop or slide 5 passing around and movable along the main band.

The object of the invention is to provide improved means for connecting the two bands together in a simple and efficient manner, and so 15 that, in the case, for example, of truss and like bands, the auxiliary or under band is prevented from sliding or moving along the main body band.

In the preferred form of the invention a fastening device is provided comprising two pairs of 20 jaws, formed conveniently by a pair of hinged or pivoted together plates, one of the jaws carrying a lever having an arm adapted to co-operate with one of the bands to be fastened together and press it against the opposed jaw, the other arm 25 of the said lever preferably having prongs or projections adapted also to engage the said band, and the arrangement is such that the movement of the lever into its operative position, to press the band against the opposed jaw, serves to 30 press the other jaws towards one another in engagement with the other band, which may, in the case of a truss, be the main body band. Where the device is applied to a truss or like 35 surgical appliance it may be carried by, or provided with, a loop or slide extending around the main body band, the one pair of jaws lying within the loop, so as to engage opposite sides of the main band, being pressed into gripping engagement with the latter when the lever is actuated.

Figure 1 of the accompanying drawings shows a truss in which the main body band and the under band are connected together by means of a device constructed in accordance with this invention.

Figure 2 is a front view of the device and of the adjacent portions of the truss bands upon a larger scale.

Figure 3 shows the device with the lever moved 50 into its unfastened position and the under band detached.

Figure 4 represents a section upon a larger scale on the line IV—IV, Figure 2.

Figure 5 is a similar sectional view but with 55 the lever turned back into its inoperative posi-

tion, so that both bands of the truss are released.

Figure 6 represents a cross-section, upon a larger scale, on the line VI—VI, Figure 2.

Figure 7 is a cross section on the line VII—VII, 5 Figure 2.

Figure 8 is a longitudinal section through the fastening device, with the truss bands detached, showing the lever in its inoperative position, and the jaws at the one end fully opened the dotted 10 lines indicating the closed position of the jaws.

Figure 9 shows a perspective view of the improved device.

Referring to the drawings, the truss comprises a main body band 1 and an under band 2 which 15 passes between the legs of the user and which is attached at its one end to a fabric loop 3 which passes around the main band 1 so that it may be slid or moved along the latter into the most suitable position when it is desired to adjust the 20 truss. According to the invention means are provided for attaching the under band 2 to the loop 3 and also, at the same time, for preventing the said loop from moving along the main band, excepting when necessary for the adjustment of 25 the truss. For this purpose a fastening device is employed comprising two pairs of jaws adapted to be operated simultaneously by means of a single lever, the device, which is hung from or carried by the loop or slide 3, being arranged so that 30 one pair of jaws engage with the main band 1, whilst the under band 2 is gripped between the lever and one of the other two jaws. The said device consists of a pair of sheet metal plates disposed one in front of or above the other and 35 pivoted together near the middle, without intersecting, by means of a hinge-pin 4 passing through flanges 5 at the edges of the one plate and through lugs 6 on the other plate, the one 40 half of the latter fitting between the flanges 5. The arrangement is such as to provide a pair of 45 opposed jaws 7 and 7a at the one end of the device, and a second pair of jaws 8 and 8a at the other end of the same, the plates being so pivoted or hinged together that when the jaws 8 and 8a are closed together the other jaws 7 and 7a are moved apart. The side edges of the jaws 7 and 7a may be turned in slightly to provide narrow gripping flanges 9 and 9a and formed across the outer end of the jaw 7a is a transverse slot 50 10 to receive the loop or slide 3 of the truss.

The two pairs of jaws are separated by a central gap or aperture 11 which extends upon both sides of the hinge-pin 4, whilst the jaw 8a is formed with a slot 12 to provide an integral 55

cross-bar 13. Hingedly mounted upon this cross-bar 13 is a two-armed lever 14 comprising a front operating arm or plate and a gripping portion 15 at right-angles thereto. The edge of this gripping portion 15 is formed with teeth or serrations 15a, whilst provided at the outer end of the front operating arm or plate of the lever are prongs 16 disposed on opposite sides of the bent-out finger-piece 17, and adapted, when the lever is turned down into its operative position, to extend over the inner edge of the jaw 8a of the device, so as to project into the gap 11 between the two pairs of jaws. The gripping portion 15 of the lever then extends towards the opposite 15 jaw 8, so that it lies substantially at right-angles thereto.

The improved fastening device is arranged to be carried by the fabric loop or slide 3 of the truss which engages over the main band 1, and for this purpose the one end of the loop 3 is inserted, before its two ends have been secured together, through the slot 10 in the front jaw 1a of the device and is passed from the front through the aperture 11 so as to lie above the hinge-pin 4; the two ends of the loop being brought down at the back of the fitting, after the loop has been passed around the main band 1, and being then secured together by sewing. The two upper jaws 1 and 1a of the device thus lie wholly within the loop 3, so that the fitting is suspended from the latter and the said jaws are arranged to engage the opposite sides of the main truss band 1 around which the loop extends. The under band 2 of the truss, on the other hand, is arranged to be passed between the jaw 8 of the device and the gripping portion 15 of the lever 14, after the latter has been first turned into its inoperative position, the end of the said under band being then passed to the front of the fitting through the aperture 11, as shown in Figure 5.

When the lever 14 is turned into its inoperative position, illustrated in Figure 5, the gripping portion 15 of the said lever 14 lies, as shown, closely against the inner face of the jaws 8a, and not only may the end of the under band 2 be inserted beneath the lever and also adjusted according to requirements but the jaws 8 and 8a may be pressed towards one another as far as permitted by the thickness of the under band 2. This causes the other pair of jaws 1 and 1a to be opened or moved further apart so that they may, together with the loop or slide 3, then be moved freely over or along the main band 1 of the truss. Thus, when the lever 14 is in its inoperative position the under band 2 may be adjusted, or inserted or removed, and the fitting, with the loop 3, may be moved along the main band 1 into the most suitable position. After the truss has been adjusted the lever 14 is turned down into its operative position, as indicated in Figure 4. This causes the part 15 of the said lever to move into a position at right-angles to the jaw 8 so that the end of the under band 2 is now pressed firmly against the latter, whilst, at the same time, the prongs 16 on the lever are caused to penetrate the material of the said under band, so that the latter is held securely in place and it is impossible for it inadvertently to move out of the position into which it is adjusted. The act of turning down the lever 14 into its operative position, as described, also results in the jaws 8 and 8a being forced further apart, as will be obvious from an inspection of Figure 4, and consequently the other

pair of jaws 1 and 1a of the fitting are moved towards one another, with the result that they are pressed closely against the opposite sides of the main truss band 1 and firmly grip the latter. The fitting, and consequently the loop 3, are thereby effectively prevented from moving around the main band 1.

By moving the lever 14 into its former inoperative position the under band 2 and loop 3 are again freed, and only a single operation is necessary either to release the under band and loop or to secure the said under band and loop in position, either operation being readily and quickly effected.

What I claim is:

1. A device for connecting together two bands, comprising a pair of spaced plate-like parts hinged together at a point intermediate their ends to form two pairs of opposed jaws at opposite ends disposed so that the jaws of the one pair move towards one another when the jaws of the other pair are moved apart, one of the plate-like parts having an aperture formed therein between the pairs of jaws, a lever-grip mounted adjacent the outer edge of one of the jaws of the apertured plate-like part and comprising an inturned portion adapted to co-operate with the opposed jaw, and an outer portion adapted to lie outside the jaw upon which the lever-grip is mounted, said outer portion having teeth engageable through said aperture with a band inserted between the jaw upon which the lever-grip is mounted and the opposed jaw, said inturned portion being adapted to hold a band against the opposed jaw to force the latter relatively outwards and thereby cause the other pair of jaws to close.

2. A device for connecting together two bands, comprising two pivoted-together spaced members forming a pair of opposed jaws at each end, said members having apertures formed therein, which are located between and separate the two pairs of jaws and through which a band can be passed, and a lever mounted adjacent the outer edge of one of the jaws, the said lever comprising an inturned heel portion adapted to co-operate with the opposed jaw to force the jaws apart and cause the other pair of jaws to close, and an outer portion having projections adapted to extend into said apertures in order to grip a band inserted between the jaw upon which said lever is mounted and the opposed jaw.

3. A device for connecting together two bands, comprising a pair of plate-like parts having side portions and being hinged together face to face at a point intermediate their ends to form at opposite ends two pairs of opposed jaws adapted to embrace the respective bands and so disposed that the jaws of the one pair move towards one another when the other two jaws are moved apart, said two pairs of jaws being respectively connected by said side portions of the plate-like parts which maintain the two pairs of jaws in spaced relation to provide a gap through which a loop surrounding one band can be passed, and a lever hinged to the outer end of one of the jaws, said lever comprising an inturned portion disposed between the jaw upon which the lever is mounted and the opposed jaw and co-operable with the latter to force said jaws apart and cause the other pair of jaws to close, and an outer portion having teeth adapted to enter the gap between the two pairs of jaws and grip a band inserted between said lever-carrying jaw and its opposed jaw.

4. A device for connecting together two bands, comprising a pair of plate-like parts having side portions and being hinged together face to face at a point intermediate their ends to form at 5 opposite ends two pairs of jaws adapted to embrace the respective bands and so disposed that the jaws of the one pair move towards one another when the other two jaws are moved apart, said two pairs of jaws being respectively connected by said side portions of the plate-like parts 10 which maintain the two pairs of jaws in spaced relation to provide a gap, gripping flanges on the side edges of the jaws of one pair, and a lever hinged to one of the jaws of the other pair, said 15 lever having an outer operating portion and an inturned portion extending between the jaws, said inturned portion being co-operable with an opposed jaw to force said other pair of jaws apart and thereby cause the first-mentioned pair to 20 close.

5. A device for connecting together two bands, comprising a pair of plate-like parts having overlapping side lugs hinged together, whereby said plate-like parts are interconnected face to face at a point intermediate their ends to form at opposite ends two pairs of jaws adapted to embrace the respective bands, said plate-like parts having opposite slots formed therein intermediate their ends to form a through gap, a jaw of one pair of jaws having a transverse slot formed 10 therein near its outer end, and a lever-grip device pivoted at the outer end of one jaw of the other pair of jaws, said device having a gripping arm co-operating with the opposite jaw to grip an inserted band against said opposite jaw and 15 co-operable therewith to cause the second-mentioned pair of jaws to separate and the first-mentioned pair simultaneously to close.
